CLAIM

The ornamental design for a vapor pad for vaporizer, diffuser, humidifier, or the like as shown and described.

DESCRIPTION

FIG. 1 is a front view of the vapor pad for vaporizer, diffuser, humidifier, or the like;

FIG. 2 is a rear view of the vapor pad for vaporizer, diffuser, humidifier, or the like;

FIG. 3 is a top view of the vapor pad for vaporizer, diffuser, humidifier, or the like;

FIG. 4 is a bottom view of the vapor pad for vaporizer, diffuser, humidifier, or the like;

FIG. 5 is a left side view of the vapor pad for vaporizer, diffuser, humidifier, or the like;

FIG. 6 is a right side view of the vapor pad for vaporizer, diffuser, humidifier, or the like;

FIG. 7 is a front perspective view of the vapor pad for vaporizer, diffuser, humidifier, or the like; and,

FIG. 8 is a rear perspective view of the vapor pad for vaporizer, diffuser, humidifier, or the like.
